UNITED STATES PATENT OFFICE.

JOHN LANZ, OF PITTSBURG, PENNSYLVANIA, ASSIGNOR TO THE CARNEGIE STEEL COMPANY, LIMITED, OF SAME PLACE.

PRESS FOR SHAPING METAL.

SPECIFICATION forming part of Letters Patent No. 634,528, dated October 10, 1899.

Application filed September 6, 1898. Serial No. 690,367. (No model.)

To all whom it may concern:

Be it known that I, JOHN LANZ, of Pittsburgh, in the county of Allegheny and State of Pennsylvania, have invented a new and useful Improvement in Presses for Shaping Metal, of which the following is a full, clear, and exact description, reference being had to the accompanying drawings, forming part of this specification, in which—

- 10 Figure 1 is a side elevation, partly in section, of my improved press. Fig. 2 is a horizontal section on the line II II of Fig. 1. Fig. 3 is a vertical cross-section of the press. Figs. 4, 5, and 6 are detail sections showing the shape of the dies and of the beam near the base of the tapering portion, at the middle of the tapering portion, and near its end, respectively; and Fig. 7 is an elevation of the finished pole, partly broken away.
- 15 My invention relates to the bending and shaping of channeled beams and other shapes, such as grooved bars, into articles such as telegraph-poles, span-wire poles for electric railways, architectural columns, &c.; and it
- 20 consists in an improved machine for carrying out this operation.

In the drawings, 2 represents the base-plate of the machine, having at each side vertical standards 3, which support the top plate 4. 30 5 is a longitudinal die-holder secured to the base-plate and having longitudinal ribs, between which is held the bottom die 6 by means of the set-screws 7. This die is provided with a central longitudinal channel which is tapered and increases in depth and width from one end toward the other. The portions at the sides of this channel are formed into ribs 8, which rise above the main plane of the top of the die and are gradually increased in 35 height and decreased in width from one end of the die toward the other. The sides of the die-body beyond these ribs are gradually tapered in width and are shaped to receive the flanges of the beam. These sides are provided with recesses placed at suitable intervals apart and in which are placed set-screws 9, having washers beneath their heads, these screws acting as adjustable gages for the beam being shaped. The upper die is made 40 in three parts, the two outer longitudinal por-

tions 10 10 being secured to the bifurcated links 11, which form the lower members of toggle-levers having corresponding upper members 12. These upper members are pivoted to the upper portion of the frame, and 55 the several levers are connected by rods 13, which are adjustable in length, as shown. These toggle-levers are operated by a lever 14, pivoted at the end of the machine and connected with the end toggle-lever by a link 60 15, this lever being operated by the motive cylinder 16, supported upon the top of the machine and having link connections 17 with the lever.

The two legs of each bifurcated lower member of the toggles are connected by square bars 18, which are guided within vertical slots in longitudinal box-guide 19, placed between these legs and secured rigidly to the frame of the machine. The central upper die 20 is 65 fitted between the side dies and is secured to the lower members 21 of another set of toggles, which are operated by a motive cylinder 22, the connections between the cylinder and the toggles being similar to that above described for the side dies. This middle die is 70 provided with vertical slots for the passage of the bars 18, so that it may move independently of the side dies.

The beam is fed into the machine over feed- 80 rollers 23 and between a pair of rollers 24, the lower of which may be moved vertically by yoke connections with the motive cylinder 25, the face of the upper roller being slightly above the level of the beam as it passes into 85 the machine. Within the machine are provided guide-rollers 26, which contact with the flanges of the beam and guide and support it in place on the lower die. The beam is stopped at the proper place upon the die by a stop 27, 90 secured to a swinging U-shaped frame 28, pivoted at 29 and connected with the journals of the lower roll 30, which is located at the exit end of the machine and has yoke connections with the cylinder 31, by which it may 95 be lifted. The U-shaped frame is provided with a roller 32, which, as the frame is moved upwardly, contacts with the projecting end of the shaped beam and lifts it after the upper dies have been retracted. In order to 100

prevent the feed-rollers 24 and 30 from injuring the hot beam, I preferably provide limit-ing-stops for the bearings of these rolls.

In order to prevent the shaped beam from 5 being lifted by the upper dies as they rise, I provide a stripper-bar 33, beneath which the end of the beam lies, this stripper being a sufficient distance above the beam so that it may be lifted into contact with the upper roll 10 34 when the lower roll 30 is lifted.

In operating the upper dies in order to prevent distortion of the beam by the action of the middle die the side dies are moved downwardly a certain distance before the middle 15 die acts upon the metal, and to perform this operation I provide a lever 35, pivoted to the frame of the machine and provided at its upper end with an adjustable stop 36, which is contacted with by the set-screw 37 upon the lever 14, so as to limit the movement of this lever, and consequently regulate the amount of descent of the side dies. A similar device is provided for the lever of the middle die.

The operation is as follows: The beam having 25 been passed into the machine with its end against the stop, the lever 35 is positioned so that the lever 14 will contact with it, and motive fluid then being admitted to the cylinder 16 the upper side dies will be moved down a 30 part of their stroke, as indicated by dotted lines in Fig. 6. Motive fluid then being admitted to the other cylinder 22, the middle upper die is forced down so as to shape the central tapering channel in the beam. The upper side 35 dies are then moved down their entire distance, the stop upon the lever 35 having been thrown aside, and the final shape is given to the web of the beam. The descent of the side dies is then regulated by the set-screw 40 37, which strikes the frame of the machine. The upper dies then being retracted, the roller 30 is lifted, and the roller 32, striking the end of the beam, lifts it free from the lower dies. The lower roll 24 is then lifted, and the upper 45 roll 24 being rotated the beam is grasped between them and being fed forward enters the bite of the rolls 30 and 34 and is drawn out of the machine. A tapered post or beam is thus formed, and this tapered portion preferably 50 extends for about one-half of the entire length of the pole, which I have shown as formed from an I-beam, the article being shown in Fig. 7.

The advantages of my invention will be 55 apparent to those skilled in the art, since a channeled beam or other shape may be quickly and easily shaped into a form suitable for posts for span-wire columns and similar purposes.

60 The particular form of pole which I have shown is of special advantage, as it tapers from about its middle portion to the top and is of great strength and stiffness, while it may be easily and cheaply formed from commercial beams.

65 The taper of the beam may be formed by cutting out a wedge-shaped piece from the

web and pressing the outer portions together, or by folding the web upon itself, or rolling a beam with a longitudinal corrugated web 70 and then forcing the corrugated portion together, or spreading the same by straightening the corrugation. Farther, the distance between the standards 3 may be increased when desired by increasing the length of 75 the top plate 4 and either increasing the length of the base 2 or providing a separate base-plate for each standard, or a greater number of standards may be provided when necessary. Many other changes may be made 80 in the form and arrangement of the machine, as well as in the shape of the beam, without departing from my invention, since

I claim—

1. A shaping-press having a longitudinal die, a reciprocating middle die coacting therewith, two separate outer dies at the sides of the middle die, said outer dies being rigidly connected to each other by cross-arms and coacting with the longitudinal die, and mechanism for reciprocating the outer dies independently of the middle die; substantially as described.

2. In a press for shaping beams, a lower longitudinal die arranged to act upon the web of the beam, and having a longitudinal tapering recess, a middle upper die arranged to coact with the recess to form a tapering channel in the web of the beam, a pair of upper side dies at the sides of the middle die, and rigidly connected together, and mechanism for reciprocating the middle upper die and the upper side dies independently of each other; substantially as described.

3. In a press for shaping beams, a lower longitudinal die arranged to act upon the web of a beam, and having a longitudinal tapering recess, a middle upper die arranged to coact with the recess to form a tapering channel in the web of the beam, a pair of upper dies at the sides of the middle die and rigidly connected together, said side dies being arranged to act upon the web of the beam at the sides of the channel, and actuating toggle connections for the middle upper die, and the upper side dies; substantially as described.

4. In a shaping-press, a lower longitudinal die, a middle upper die, two upper dies at the sides of the middle die, and rigidly connected together, actuating toggle connections for the middle die, and separate toggle connections for the connected side dies, the upper bearings of one set of toggle-links being separate from those of the others; substantially as described.

5. In a shaping-press, a pair of upper side dies secured to the bifurcated members of toggles, means for operating the toggles, a middle upper die having vertical slots through which extend cross-bars connecting the legs of the bifurcated members of the toggles, and another set of toggles arranged to actuate the middle upper die; substantially as described.

6. A shaping-press having at one end a swinging stop pivoted upon an axis below the level of its contacting portion, said stop having a lower lifting-arm, and mechanism for 5 swinging the stop upwardly from in front of the metal, and thereby at the same time lifting the metal; substantially as described.

7. A shaping-press having a pair of rollers at the exit end, means for moving the lower 10 roller vertically, and a swinging stop con-

nected to the lower roller and having a lifting-arm arranged to lift the metal; substantially as described.

In testimony whereof I have hereunto set my hand.

JOHN LANZ.
